UNITED STATES PATENT OFFICE.

IRA OTTO ADAMS, OF DURANT, IOWA.

TENSION-INDICATING DEVICE FOR SEWING-MACHINES.

1,289,066.

Specification of Letters Patent. Patented Dec. 31, 1918.

Application filed April 29, 1918. Serial No. 231,469.

To all whom it may concern:

Be it known that I, IRA O. ADAMS, a citizen of the United States, residing at Durant, in the county of Cedar and State of Iowa, 5 have invented new and useful Improvements in Tension-Indicating Devices for Sewing-Machines, of which the following is a specification.

This invention relates to indicating devices and has for its object the provision of a device adapted primarily for use in connection with domestic sewing machines, whereby to provide means for ascertaining whether or not the tension upon the upper 10 and lower threads is equal.

It is well known to users of sewing machines that unless the tension upon the upper thread is the same as the tension upon the lower thread, the stitches will either pucker 20 up the cloth or tear out, unless the thread breaks. As each thread has a separate tension adjustment it is a very difficult matter and purely a matter of guess work to attempt to so adjust the tensioning devices 25 that both threads will be held under exactly the same tension. It is with this well known fact in mind that the present invention has been designed which has as an important object, the provision of a tension indicating 30 device which is extremely simple and which may be operated without any degree of mechanical skill, which will be inexpensive to manufacture, and which will fulfil its indicating function in a thoroughly efficient and 35 reliable manner.

With these and other objects and advantages in view, the invention consists in the novel construction and arrangement to be hereinafter more fully described and claimed 40 and illustrated in the accompanying drawing, in which—

Figure 1 is an elevation of the device in use and engaged by the upper and lower threads of a sewing machine.

Fig. 2 is a longitudinal sectional view therethrough, and,

Fig. 3 is a detail view illustrating a slightly modified form.

Fig. 4 is a fragmentary perspective view 50 illustrating a slight modification of the thread engaging means.

Referring more particularly to the drawing, the letter A designates the upper thread coming from the needle of a sewing machine, 55 and B designates the lower thread coming

from the bobbin. Certain parts of the sewing machine are shown in more or less diagrammatic outline for better illustrating the application of my invention.

My device comprises a body 5 stamped or otherwise formed preferably from sheet-metal and including a main relatively large portion 6 having extending centrally from the rear edge thereof, an integral handle 7 and having extending centrally of its forward edge a reduced extension 8 apertured as shown at 9. This constitutes the relatively fixed portion of the device.

Disposed upon the relatively large portion 6 of the supporting plate and spaced therefrom by a suitable washer 10, is a movable member 11 formed substantially crescent-shaped with the forwardly projecting horns 12 and provided with an integrally formed pointer 13. The movable member 11 is provided with an aperture 14 registering with the aperture 9 of the extension 8, provided for the passage of a securing bolt 15 having its threaded end provided with a nut 16. These parts are so arranged that the movable member 11 is freely revoluble upon the extension 8. When the member 11 is moved upon the pivoting bolt 15 the point of the pointer 13 will move in the arc of a circle and in order that the degree of the inclination of the axis of the member 11 in relation to the axis of the supporting member 5 may be determined, I provide upon the plate portion 6, a number of spaced arcuate lines 17 struck from the pivot point 15 as a center and intersected by radial division lines 18.

As shown in Fig. 1, the horns 12 are provided with angularly extending heads 19 disposed at a very acute angle to the outer edges of the horns, whereby a thread receiving notch is formed. I preferably, though not necessarily, further provide the horns 12 with grooves 20 extending diagonally across the horns to the vertices of the notches therein, these grooves serving as thread guiding and retaining means.

Instead of providing the well defined notches shown in the preferred form, I may, as shown in Fig. 3, form the ends of the horns with reduced necks 21 terminating in enlarged heads 22, omitting the grooves, or not, if desired. In this form the threads would be retained upon the horns by tying them or looping them around the necks 21.

In use, the upper and lower threads A and B are pulled a sufficient distance away from the needle and presser foot of the sewing machine and are then caught in the 5 grooves 20 and notches and, if necessary, looped around the horns, so that they will not slip. The operator then grasps the device by the handle 7 and exerts a gentle pull thereon in a plane intermediate the 10 points of emergence of the threads A and B from the upper and lower guides, respectively. If the tension on both threads is the same, there will be no movement of the member 11 and the pointer 13 will have its 15 point disposed in alinement with the central graduations on the plate 6. If, however, the tension on one thread is greater than the tension on the other, the member 11 will swing upon its pivot 15, the degree of movement 20 depending upon the difference in tension, and the pointer 13 will be correspondingly moved. If the tension is thus found to be unequal, the independent adjusting devices are adjusted in the customary manner 25 until a pull upon the handle 7 will result in no angular movement of the member 11.

From the foregoing description and a study of the drawing it will be apparent that 30 I have thus provided an extremely simple and efficient device whereby any, even slight, difference between the tension on the upper and lower threads may be readily detected so that proper adjustment may be made. 35 It will of course be understood that the embodiment of my invention shown and described is merely illustrative, as I reserve the right to make such changes in the form, construction and arrangement of parts as 40 will not depart from the spirit of the invention nor the scope of the subjoined claims.

Having thus described my invention what is claimed is:

1. A device of the character described comprising a relatively stationary plate 45 provided with graduations, a relatively movable plate disposed flat upon and pivotally connected with said relatively stationary plate, an indicator hand formed on said movable plate and movable over said graduation, a handle on said relatively stationary plate, and laterally extending arms formed on said movable plate and provided with thread engaging notches.

2. A device of the character described 55 comprising a relatively stationary plate provided with graduations and having a handle thereon, a movable member disposed flat upon and pivotally connected with said relatively stationary plate and formed as a 60 plate having an indicator hand formed integrally thereon and traveling over said graduations, said movable plate being provided at opposite sides of its pivot with thread engaging notches. 65

3. A device of the character described comprising a plate provided with graduations and having a handle formed thereon, a movable member pivoted on said plate and having an indicator hand movable over 70 said plate and coöperating with the graduations thereon, said movable member being provided with notches on either side of its pivot for engagement of a number of threads under individual tension, a difference 75 between the tensions resulting in pivotal movement of said movable member upon rectilinear pull upon said handle.

In testimony whereof I affix my signature.

IRA OTTO ADAMS.
